United States Patent Office

Des. 219,112
Patented Nov. 3, 1970

219,112

CIGARETTE LIGHTER

Frank H. Stephens, Jr., Dunwoody, Ga., assignor to Scripto, Inc.

Filed Mar. 6, 1969, Ser. No. 16,081

Term of patent 14 years

Int. Cl. D27—05

U.S. Cl. D48—27

FIG. 1

FIG. 2

FIG. 3

FIG. 4

FIG. 5

FIG. 6

FIG. 1 is a front elevational view of the cigarette lighter of my design;

FIG. 2 is a rear elevational view thereof;

FIG. 3 is a left end elevational view of the lighter shown in FIG. 1;

FIG. 4 is a right end elevational view of the lighter shown in FIG. 1;

FIG. 5 is a top plan view of the lighter shown in FIG. 2; and

FIG. 6 is a bottom plan view thereof.

I claim:

The ornamental design for a cigarette lighter, as shown.
